UNITED STATES PATENT OFFICE.

SAMUEL J. WENTWORTH, OF NEWPORT, KENTUCKY, AND FREDERICK H. PERRY, OF BEVERLY, MASSACHUSETTS, ASSIGNEES, BY MESNE ASSIGNMENTS, TO UNITED SHOE MACHINERY CORPORATION, OF PATERSON, NEW JERSEY, A CORPORATION OF NEW JERSEY.

HEEL-SEAT-FITTING MACHINE.

1,307,285.

Specification of Letters Patent. Patented June 17, 1919.

Application filed September 14, 1915. Serial No. 50,622.

To all whom it may concern:

Be it known that we, SAMUEL J. WENTWORTH and FREDERICK H. PERRY, citizens of the United States, residing at Newport, in the county of Campbell and State of Kentucky, and Beverly, in the county of Essex and State of Massachusetts, respectively, have invented certain Improvements in Heel-Seat-Fitting Machines, of which the following description, in connection with the accompanying drawings, is a specification, like reference characters on the drawings indicating like parts in the several figures.

This invention relates to machines for operating upon boots and shoes and is herein illustrated in connection with a machine for forming upon the heel portion of the sole of a shoe a convex heel seat to fit into the concavity of the heel which is to be attached.

In the manufacture of shoes it is customary to attach the rough heel and then to trim the heel and the edge of the heel portion of the sole simultaneously, and later to scour and burnish them. With wooden heels, however, this procedure is not practicable since to trim a wooden heel and the edge of a leather sole simultaneously in a satisfactory manner would be difficult. Moreover a wooden heel is commonly covered with a thin veneer of leather or celluloid which cannot be subjected to the scouring operation without injury. Accordingly a wooden heel is completely finished before being attached; and the edge of the heel portion of the shoe is trimmed off so as to permit the upper edge of the heel to extend close to the upper of the shoe. A wooden heel has a concavity in its upper face; and the trimming of the heel portion of the sole is such as to provide a raised seat to receive this concavity, the forward end of the seat terminating in a shoulder against which the upper forward end of the heel may abut.

The general object of the present invention is to produce an improved machine for removing stock from the heel portion of the sole of a shoe prior to the heel attaching operation to provide a seat for the concavity of a heel; and the illustrative machine is an improvement upon the machine shown in the

application of S. J. Wentworth Serial No. 875,468.

An important feature of the invention relates to the provision in a machine of the class described of means for producing an undercut shoulder at the end of the heel seat. Wooden heels are commonly of the Louis type having projecting lips at their upper forward ends. In order to make a smooth joint at the junction of the breast of such a heel with the shank of the sole the projecting upper forward portion of the heel is inserted beneath the undercut shoulder.

This and other features of the invention, including certain details of construction and combinations of parts, will be described as embodied in an illustrative machine and pointed out in the appended claims.

Referring now to the accompanying drawings,—

Figure 1 is a side elevation of a machine in which the present invention is embodied;

Fig. 2 is a perspective of the upper portion of the machine;

Fig. 3 is a perspective of the heel portion of a shoe the sole of which has been operated upon by the machine;

Fig. 4 is a perspective showing more particularly the mechanism for adjusting the position and for opening the jaws which support the shoe;

Fig. 5 is a plan of the supporting jaws and the mechanisms for adjusting and operating them.

Mounted in horizontal ways in the frame 1 of the machine is a slide 3 having a horizontally projecting portion to which the trimming knife 5 is fastened. The presser roll 7 is carried by an arm 9 the forked rear end of which is pivoted upon a swinging stud 11 suspended by a link 13 from a stud 15 which is carried by the slide 3. Passing through the forward portion of the arm 9 is a pin 17 suspended from a second pin 18 by links 19, said second pin also passing through the forward end of a two-part lever 21, 23. Both parts of this lever are pivoted about a stud 25 carried by the slide 3, a projection 123 on the lever 23 being arranged to contact normally with a projection 121 on the lever 21, the two parts being held in the

position shown by a heavy flat resilient bar 27 the tension of which may be adjusted by means of a thumb screw 29 which passes through the part 23 and contacts with said bar.

In the operation of the machine, after the shoe is in place, the first operation is to bring the presser roll 7 down upon the sole of the shoe. This is effected in the following manner:—Toggle links 33 and 35 are pivoted respectively upon a pin 37 carried by the part 23 and upon a pin 39 carried by the slide 3. An arm 41, which is normally held in the position shown by a spring 42 is provided with studs 43, 45 carrying rolls 47 and 49 said arm being fast to or a part of the hub of the toggle link 35. When the machine is started the end of an arm 51 is brought down upon the roll 47 thereby swinging the arm 41 downwardly and straightening the toggle to cause the presser roll to be forced down upon the sole of the shoe through the resilient bar 27. At the same time the roll 45 enters the open end of an upwardly inclined track 53 the angular position of which may be varied after the clamping bolt 55 has been loosened. By adjusting the angular position of the track 53 the descent of the roll 7 may be controlled. In other words the roll may be caused to depress the sole more at one point than at another.

Inasmuch as the presser roll 7 must always be brought down upon the sole of the shoe at a point just forward of the curved base of the jaws which support the edge of the sole while the stroke of the knife must be long enough to take care of any length of heel seat and consequently of any horizontal position to which the roll 7 may be adjusted, the knife is caused to start its horizontal motion before that of the roll 7 and to pick up and carry along the roll when the forward edge of the knife has reached a position close to the lowermost point of said roll. With the construction of the parts thus far described if forward movement is imparted to the slide 3 no forward movement will at first be imparted to the roll 7 since the link 13 will merely swing about the stud 11. Forward movement of the roll is brought about by a pull exerted upon the stud 11 by a link 57, said link being pivoted at its forward end to upstanding ears of a slide 59 mounted in suitable ways in the horizontal projection of the slide 3. This slide 59 carries a box 61 in which is a transversely slidable latch 63 the ends of which project angularly toward the rear of the machine as shown. The outer end of this latch normally lies in an angularly disposed socket 64 in a part 65 which is stationary during the operation of the machine but is slidable in the frame and may be adjusted horizontally to provide for

different lengths of heel seats as will presently be described. The inner end of the latch is adapted to be received and drawn into a socket 67 formed in a part of the slide 3. The rear walls of these two sockets project toward each other, that is toward the center of the slide 59, more than do the forward walls; consequently when the slide 3 is moved forward the projecting portion of the rear wall of the socket 67 draws the latch 63 out of the socket 64 and into the socket 67 whereupon, as the slide 3 moves farther forward, a pull is exerted upon the link 57 to cause the roll 7 to travel forward in unison with the trimming knife 5. On the return movement of the slide 3 the outer corner of the latch 63 is caught by the projecting wall of the socket 64 and drawn into said socket so that when the one-revolution clutch, presently to be referred to, brings the machine to rest, the parts will be in the position shown. The arm 51 is operated by means of an upright rod 69 from a cam 71 mounted on the driving shaft 73.

Referring now more particularly to Figs. 4 and 5, the construction, operation and adjustment of the jaws 75 which support the projecting heel portion of the sole will be described. These jaws are pivoted at 77 on the member 65 which, as has been stated, is a slide member and may be adjusted horizontally. One of the jaws 75 has a tail 79 to which is pivoted a rod 81, said rod being contained in a socket 165 which is integral with the slide 65. A spring 83 surrounds a reduced portion of the rod and may be compressed as desired by turning a threaded sleeve 85. A nut 87 on the end of the rod 81 holds the parts in the position shown and determines the normal distance between the two jaws 75. The rear portion of the jaws 75 near the pivots 77 are provided with intermeshing teeth 89 to insure that the angular movement of the jaws shall always be equal and in opposite directions. In order to open the jaws preparatory to placing a shoe in position, an arm 91 having an elongated flat operating face 93 is carried by two parallel-motion arms 95, the hub of the right hand arm being connected with a rod 97, to the lower end of which is attached a treadle 99. The operating face of the arm 91 is elongated because, as has been explained, the member 65 by which the jaws are carried is horizontally adjustable. This horizontal adjustment is accomplished through a roll 101 carried on the under side of the slide 65, said roll extending into the track of a barrel cam 103 pivoted at 105 to the frame of the machine. Integral with the hub of the barrel cam is an arm 107 carrying at its outer end a spring pressed pin 109 which is fast to a knurled handle 111, said pin being adapted to register with any one of a plurality of

sockets 113 in a scale formed on the frame of the machine. The sockets may be numbered in any suitable manner as shown in Fig. 2 to facilitate locating the position of the slide 65.

When the shoe is brought to the present machine it commonly contains no last and is placed upon the jack 115, said jack being pivoted at its lower end to the frame of the machine and being adapted to be held in the position shown in Fig. 2, by means of pawls 117 which are fast to a rod 119 and cooperate with a rack 125, a handle 127 being provided to lift the pawls when it is desired to swing the jack into the position shown in Fig. 1. The upper surface of the jack when in the position shown in Fig. 2 lies somewhat below the under surface of the thin jaws 75 so that the roll 7 may depress the middle of the heel portion of the sole. In order, however, to hold the shoe up so that the jaws will properly enter the crease between the sole and the upper when the jack is moved from the position shown in Fig. 1 to that shown in Fig. 2 a spring pressed pin 129 is mounted near the rear end of the jack.

The trimming knife 5 forms upon the heel portion of the sole a horseshoe-shaped rand which is removed by the knives mounted in an approximately vertical slide 131. This slide is mounted in a guide member 133 pivoted to the frame of the machine about the stud 135 and adapted to be held in adjusted angular position by means of a pin 137 which may be put through any one of a series of holes 139 in a flat plate forming a portion of the frame of the machine and into a socket in the guide member 133. The axis of the stud 135 lies in the path of movement of the trimming knife so that the lowermost positions of the edge of the cutting-off knife will be substantially the same irrespective of the angles of inclination of the guide member 133. The slide 131 has a projecting arm provided with a vertical slot 141 to receive a bolt 143 by which the knife holder 145 is attached to said arm, an adjusting screw 147 being provided to move the knife holder up and down when the bolt 143 has been loosened. The holder 145 has a horizontal flange or shelf 245 provided with a downwardly extending pin upon which are hinged the adjacent sides of two blade holders 149 each blade holder being connected by a link 151 with a stud 153, said stud being adapted to be clamped in adjusted position in a slot in said shelf 245. By moving the stud 153 the angles which the planes of the blades make to each other may be varied. Inasmuch as the blades 155 have to produce cuts the bases of which slope upwardly as shown in Fig. 3, said blades are fastened to their holders by means of bolts 157 which pass through comparatively large holes in

said knives and are threaded into said holders. The purpose of adjusting the blades 155 in a horizontal path about the pivot of the hinge is to produce a curved cut across the sole of the shoe. At the time the blades act the heel portion of the sole is distorted by having its middle portion depressed with respect to its edges. With the sole thus held a cut made by a straight edged knife at an angle of more or less than ninety degrees to the axis of curvature of the sole will result in a curved cut when the sole resumes its normal flat state. With some heels such a curved cut is desirable. When a straight cut is desired the edges of the blades are brought into line in a plane which intersects the axis of curvature of the sole at right angles. It should be noted that angular adjustment of the guide member about the axis of the stud 135 permits the angle of the face of the shoulder at the forward end of the heel seat to be varied. In Fig. 3, the face of this shoulder is shown as vertical, but in many instances manufacturers prefer that it should be inclined and particularly that it should be inclined upwardly to the rear of the shoe so as to produce an undercut shoulder beneath which the upper, forward, projecting end of the heel may be inserted.

The slides 3 and 131 are reciprocated as follows: Fast to the slide 3 is a rack 159 which meshes with a pinion 161 rotatable upon fixed bearings. A vertically disposed rack 163, which meshes with this pinion, is pivoted at 167 to a rod 169 the lower end of which is pivoted at 171 to a lever 173 the other end of said lever being pivoted at 175 to the frame of the machine. A roll 177, carried by said lever, runs in a cam track 179. Turning now to the slide 131, said slide is pivoted to a rod 181, the lower end of which is pivoted at 183 to a lever 185, the other end of which is mounted on the pivot 175. A roll 187 carried by said lever runs in a cam track 189. The shaft 73, to which the cam member is fast, is actuated from a suitable source of power through a one-revolution clutch (not shown) when a treadle 191 is depressed. The lever 51, as has been explained, is operated from a roll on the lower end of the rod 69 which runs on a cam 71; and all the cams which have been referred to are formed in a member which is fast to the shaft 73.

The operation of the machine is as follows:

The handle 111 is manipulated to adjust the jaws 75 longitudinally in accordance with the length of the heel seat which is to be formed; and the blades 155 properly adjusted in both their horizontal and vertical paths. The shoe to be operated upon having been placed upon the jack 115 and the jaws 75 opened by depressing the treadle 99, the

jack is swung forward from the position shown in Fig. 1 to that shown in Fig. 2, the pawls 117 coöperating with the rack 125 to hold the jack from swinging back. The treadle 99 is then released whereupon the jaws 75 move into supporting position beneath the projecting heel portion of the sole of the shoe. The treadle 191 is then depressed to cause the shaft 73 to make one revolution. Upward movement of the rod 69 straightens the toggle 35, 37 to bring the presser roll 7 down upon the middle of the heel end of the sole; downward movement of the rod 169 moves the slide 3 together with the knife 5 forward, and presently, the latch 63 causes the roll 7 to be moved in unison with the knife. This movement in unison of the knife and roll causes the formation on the heel portion of the sole of a horse-shoe-shaped tongue which is removed by the descent of the chopping knife due to a downward pull by the rod 181. All of these movements take place during a portion of a revolution of the shaft 73; the completion of the revolution returns the power actuated parts to their normal position which is the one shown in Fig. 1. The operator then manipulates the handle 127 to release the jack, after which he swings the jack to the position shown in Fig. 1 removes the first shoe and places another upon the jack.

The cavity in the top of the heel which is to be attached generally presents a true concave surface, but the surface of the heel seat is not necessarily truly convex. The terms concave and convex, however, have been used to promote brevity since these terms define the formations with sufficient clearness and since it is obviously immaterial whether the surfaces referred to are truly convex and concave. By referring to Fig. 3 it will be seen that the heel seat extends on an incline from substantially the line of junction of the upper with the sole to a line considerably inside said line of junction.

The invention has been illustrated and described as embodied in a machine which shapes the heel portion of a sole to receive the usual concavity in the top of a wooden heel, but it should be understood that this has been done to promote brevity and that the invention in its broader aspects is not limited to the particular form of heel seat which has been shown and described.

Although the invention has been set forth in connection with a particular machine, it should be understood that the invention is not limited in the scope of its application to the particular machine shown and described.

Having thus described our invention, what we claim as new and desire to secure by Letters Patent of the United States is:

1. A machine for operating upon the sole of a shoe subsequent to its incorporation in

the shoe but prior to the attaching of the heel having, in combination, a cutter, means for positioning the shoe so as to cause the cutter to bevel the edge face and a portion of the tread face of the heel end of the sole by a cut which extends substantially from the junction of the upper with the sole to a line sufficiently inside said line of junction to provide a seat to receive the cavity formed in the top of the heel which is to be attached, and power actuated means for operating said cutter.

2. A machine for operating upon the sole of a shoe prior to the attaching of the heel, having, in combination, means for supporting a shoe, mechanism for removing stock from the heel portion of the sole to form a convexity to fit the concavity of the heel which is to be attached and treadle controlled power actuated means for causing said removing mechanism to operate, said removing mechanism being adjustable to vary the length of said concavity.

3. A machine for operating upon the sole of a shoe prior to the attaching of the heel, having, in combination, means for supporting a shoe, mechanism for cutting from the heel portion of the sole a horseshoe-shaped tongue and for subsequently cutting off the tongue, and treadle controlled power actuated means for causing said mechanism to operate.

4. A machine for operating upon the sole of a shoe prior to the attaching of the heel, having, in combination, means for supporting a shoe, mechanism for cutting from the heel portion of the sole a horseshoe-shaped tongue and for subsequently cutting off the tongue, and treadle controlled power actuated means for causing said mechanism to operate, said mechanism being adjustable to vary the length of said concavity.

5. A machine for operating upon the sole of a shoe prior to the attaching of the heel having, in combination, a support for the projecting heel portion of the sole, a presser and a knife constructed and arranged to act together on said heel portion to form thereon a convexity to fit the concavity of the heel which is to be attached, means for reciprocating said knife, and lost motion connections between said knife and presser so arranged that said knife picks up said presser after the reciprocating movement begins and drops said presser before said reciprocation ends.

6. A machine for operating upon the sole of a shoe prior to the attaching of the heel, having, in combination, means for supporting the projecting heel portion of the sole, mechanism for depressing the middle part of said heel portion, a cutting tool, mechanism for causing said tool to cut along the edge of the heel portion so depressed and

supported, a second cutting tool, mechanism for causing said second tool to cut into the edge of the sole so arranged that the heel portion of the sole is given a convexity to fit the concavity of the heel which is to be attached, and treadle controlled power actuated means for operating said mechanisms.

7. A machine for operating upon the sole of a shoe subsequent to its incorporation in the shoe but prior to the attaching of the heel, having, in combination, a support for the projecting heel portion of the sole, a presser roll, means including a positively operated member for moving said roll down upon the sole to depress the middle part of the heel portion thereof; and means acting in conjunction with said roll for trimming off said projecting portion on a bevel.

8. A machine for operating upon the sole of a shoe prior to the attaching of the heel, having, in combination, a support for the projecting heel portion of the sole, a presser adapted to traverse the middle part of the heel of the sole, means including a positively operated member for moving said presser down upon said sole, a trimming knife arranged to act in the rear of and close to said presser, means for moving said trimming knife and presser along said sole to produce a tongue on the heel portion thereof, and means for removing said tongue.

9. A machine for operating upon the sole of a shoe prior to the attaching of the heel, having, in combination, a support for the projecting heel portion of the sole, a presser arranged to act upon the middle part of the heel of the sole, a trimming knife arranged to move with said presser during the trimming operation, means including a positively operated member for moving said presser down upon said sole, means for moving said knife and presser along said sole to form a tongue on said sole, and means for cutting off said tongue.

45 10. A machine for operating upon the sole of a shoe prior to the attaching of the heel, having, in combination, a support for the projecting heel portion of the sole, a spring pressed presser arranged to act upon the middle part of the heel of the sole, a trimming knife arranged to move with said presser during the trimming operation, positively operated means acting through the spring for moving said presser down upon said sole, means for moving said knife and presser along said sole to form a tongue on said sole, and means for cutting off said tongue.

60 11. A machine for operating upon the sole of a shoe prior to the attaching of the heel, having, in combination, a support for the projecting heel portion of the sole, means for exerting pressure upon the middle part of said heel portion to distort said heel portion,

a trimming knife arranged to cut along the 65 edge of a sole so supported and distorted to form a horseshoe-shaped rand, and a cutting-off knife adapted to sever the rand so formed, said cutting-off knife being held from movement in the direction of movement of said trimming knife.

12. The combination with a presser and a knife constructed and arranged to act together upon a piece of stock, of means for reciprocating the knife, means for positively 75 connecting the presser with the knife during a part of the forward half and a part of the rearward half of the reciprocation of the knife, and means for disconnecting the presser from the knife before the reciproca- 80 tion ends.

13. A machine for operating upon the sole of a shoe prior to the attaching of the heel, having, in combination, a support for the projecting heel portion of the sole, a trimming knife, means for moving said knife over said support, a presser located in advance of said knife to distort said heel portion prior to the action of said knife, said support and presser being adjustable in the 90 direction of travel of said knife, and connections between the knife moving means and the presser so arranged that first the knife moves forward alone and then the presser moves with it. 95

14. A machine for operating upon the sole of a shoe prior to the attaching of the heel, having, in combination, a support for the projecting heel portion of the sole, means for depressing the middle part of said heel portion, a trimming knife arranged to cut along the edge of the heel portion of a sole so depressed and supported, and a cutting-off knife arranged to move in a path at an angle to that of the trimming knife, the 100 paths of the knives intersecting and being of constant lengths, said support being adjustable in the direction of the path of movement of the trimming knife to vary the 105 length of the heel seat formed. 110

15. A machine for operating upon the sole of a shoe prior to the attaching of the heel, having, in combination, a pair of jaws for supporting the projecting heel portion of the sole, means for pressing upon the middle of the heel portion to distort said portion, means for forming a heel seat on a sole so supported, a jack for presenting the shoe to the jaws, and means tending to hold the shoe spaced from the jack. 115 120

16. A machine for operating upon the sole of a shoe prior to the attaching of the heel, having, in combination, a support for a shoe, a knife for cutting from the heel portion of the sole a horseshoe-shaped tongue, and a knife for cutting off said tongue, said last-named knife being adjustable to vary the angle of its cut. 125

17. A machine for operating upon the sole of a shoe prior to the attaching of the heel, having, in combination, a support for a shoe, a trimming knife movable over said support and a cutting-off knife movable at an angle to the path of the trimming knife, said cutting-off knife comprising a plurality of blades adjustable about an axis which lies in the path of movement of said trimming knife. 65
18. A machine for operating upon the sole of a shoe prior to the attaching of the heel, having, in combination, a substantially horizontal support for a shoe, a trimming knife movable over said support, and a cutting-off knife movable in a substantially vertical path, said cutting-off knife comprising a plurality of sections and a substantially vertical pivot about which said sections are adjustable. 70
19. A machine for operating upon the sole of a shoe prior to the heel attaching operation, having, in combination, a support for the shoe, a trimming knife movable over said support, and a cutting-off knife, an angularly adjustable carrier in which said knife is mounted, said knife comprising a plurality of blades adjustable with respect to one another. 75
20. A machine for operating upon the sole of a shoe prior to the heel attaching operation, having, in combination, a support for the shoe, a trimming knife movable over said support, and a cutting-off knife, an angularly adjustable carrier in which said knife is mounted, said knife comprising a plurality of blades adjustable in two directions with respect to one another. 80
21. A machine for operating upon the sole of a shoe subsequent to its incorporation in the shoe butt prior to the attaching of the heel, having, in combination, means for progressively distorting the heel portion of the sole, and means for removing stock from the margin of said heel portion, said first named means being constructed and arranged to vary automatically the degree of distortion during the stock removing operation. 85
22. A machine for operating upon the sole of a shoe prior to the attaching of the heel, having, in combination, means for supporting a shoe and holding it stationary during the operation of the machine, mechanism for removing stock from the heel portion of the sole to fit the concavity of the heel which is to be attached, and power actuated means for causing said removing mechanism to operate. 90
23. A machine for operating upon the sole of a shoe prior to the attaching of the heel, having, in combination, means for supporting a shoe, mechanism for removing stock from the heel portion of the sole to form a convexity to fit the concavity of the heel which is to be attached, said convexity being so located as to form shoulders adjacent the shank of the sole to serve as abutments for the forward end of the heel, and power actuated means for causing said removing means to operate. 95
24. A machine for forming upon the heel portion of a sole a seat to receive the upper portion of the heel which is to be attached, having, in combination, mechanism for cutting on a bevel around the margin of the heel portion, mechanism for cutting in a direction at an angle to the first cut, and power actuated means for causing said mechanisms to operate. 100
25. A machine for operating upon the heel portion of a sole to prepare it to receive a heel, having, in combination, means for cutting around the margin of the heel to provide a raised seat to receive the cavity in the top of the heel, and means for forming an undercut shoulder at the forward end of the seat against which the upper forward end of the heel may abut. 105
26. A machine for operating upon the attached sole of a shoe prior to the attachment of the heel, having, in combination, a cutter adapted to bevel the margin of the heel end of the sole by a cut which extends substantially from the line of junction of the upper with the sole to a line located a sufficient distance inside said line of junction to provide a seat to receive the cavity formed in the top of the heel which is to be attached, and power actuated means for operating said cutter. 110
27. A machine for operating upon the attached sole of a shoe prior to the attaching of the heel, having, in combination, means for engaging the rand crease, means for cutting around the heel end of the sole on an incline from substantially the line of junction of the upper with the sole to a line sufficiently inside said line of junction to provide a seat to receive the cavity in the top of the heel which is to be attached, and power actuated means for operating said cutting means. 115
28. A machine for operating upon the sole of a shoe prior to the attaching of the heel, having, in combination, mechanism for removing stock from the rear portion of the sole to adapt it to fit the shape of the upper portion of the heel which is to be attached and for producing a curved shoulder against which the upper forward curved end of the heel may abut, means for operating said mechanism, and means for varying the curvature of the shoulder. 120
29. A machine for operating upon the sole of a shoe prior to the attaching of the heel, having, in combination, mechanism for forming on the rear portion of the sole a raised seat to receive a cavity in the upper

face of the heel and for producing a curved shoulder against which the upper forward curved end of the heel may abut, and means for varying the curvature of the shoulder.

30. A machine for operating upon the sole of a shoe prior to the attaching of the heel, having, in combination, means for making an inclined cut on the margin of the rear portion of the sole to form a heel seat, means for cutting across the sole on a curve to provide a curved shoulder against which the upper forward curved end of the heel may abut, and means whereby the curvature of the shoulder may be varied to provide for differently shaped heels.

31. A machine for operating upon the sole of a shoe prior to the attaching of a heel, having, in combination, means for supporting the sole, mechanism for removing stock from the heel portion of the sole to form a seat to fit the shape of the upper portion of the heel which is to be attached and for forming an undercut shoulder at the end of

the seat against which the upper forward end of the heel may abut, and means for operating said mechanism.

32. A machine for operating upon the sole of a shoe subsequent to its attachment to the shoe but prior to the attaching of the heel, having, in combination, means engaging the under side of the rear portion of the sole to support it, mechanism for removing stock from said rear portion so supported to adapt it to fit the shape of the upper portion of the heel which is to be attached, and power actuated means for operating said mechanism.

In testimony whereof I, the said SAMUEL J. WENTWORTH, have signed my name to this specification.

SAMUEL J. WENTWORTH.

In testimony whereof I, the said FREDERICK H. PERRY, have signed my name to this specification.

FREDERICK H. PERRY.
